UNITED STATES PATENT OFFICE.

HARRY P. DICKINSON, OF NEWARK, NEW JERSEY.

DESIGN FOR A RING.

45,860.

Specification for Design.

Patented June 2, 1914.

Application filed March 14, 1914. Serial No. 824,823. Term of patent 14 years.

To all whom it may concern:

Be it known that I, HARRY P. DICKINSON, a citizen of the United States, residing at Newark, in the county of Essex and State of New Jersey, have invented a new, original, and ornamental Design for Rings, of which the following is a specification, reference being had to the accompanying drawing, forming part thereof.

Figures 1 and 2 of the drawing represent

respectively side views of a ring showing my new design, and Fig. 3 represents a top plan view of such a ring.

I claim:

The ornamental design for a ring, as shown.

HARRY P. DICKINSON.
